UNITED STATES PATENT OFFICE.

JOHN F. O'CONNOR, OF CHICAGO, ILLINOIS, ASSIGNOR TO W. H. MINER, INC., OF CHICAGO, ILLINOIS, A CORPORATION OF DELAWARE.

ANTIFRICTION BEARING.

Application filed February 5, 1926. Serial No. 86,161.

This invention relates to anti-friction bearings.

One object of the invention is to provide a simple, practical and efficient anti-friction bearing, especially adapted for a railway car side bearing, in which the parts are so arranged that the anti-friction element is automatically returned to normal centered position when free from load.

10 Another object of the invention is to provide a side bearing of the character above referred to, in which a vertically adjustable bearing plate is utilized upon which an anti-friction element operates, in conjunction with 15 mechanism for centering said element, including means disposed at opposite sides thereof and normally bearing upon the same, which means are so arranged as to yieldably maintain said centering mechanism and said 20 element in assembled relation with respect to the bearing, while permitting detachment of the centering mechanism and element from the bearing to gain access to the bearing plate for the purpose of adjusting the same.

25 Other and further objects of the invention will more clearly appear from the description and claims hereinafter following.

In the drawings forming a part of this specification, Fig. 1 is a vertical sectional view 30 taken through the ends of the body and truck bolsters of a railway car and through the side bearing, showing my improvements in connection therewith. Fig. 2 is a fragmentary top plan view of the bearing illustrated in 35 Fig. 1, showing the same detached from the truck bolster. Fig. 3 is a transverse vertical sectional view of the invention taken substantially on line 3—3 of Fig. 1. And Fig. 4 is a fragmentary vertical sectional view similar 40 to Fig. 1, showing a slightly different embodiment of the invention.

Referring first to Figs. 1 to 3, inclusive, of the drawings, 10 denotes the underside of the body bolster and 11 the upper side of the corresponding truck bolster. The improved side bearing is shown as applied to the truck bolster and comprising broadly a mounting, retainer or housing A; an adjustable bearing plate B, anti-friction element C; and centering means D—D.

The housing or retainer A comprises a generally rectangular boxlike member having side walls 20—20, end walls 21—21, and a bottom 22. Laterally extending securing lugs 50 102 are disposed adjacent each end of the

housing or retainer, which may be secured to the plate 11 by rivets 103 as shown in Fig. 1. The side walls 20—20 of the housing are inwardly offset toward each other as indicated at 23—23 to provide at each side of the housing oppositely disposed abutments 24—24 extending vertically from the top to bottom of the housing. Said side walls are further provided with vertically disposed slots or openings 25—25 adapted to permit the insertion of a bar into the housing for prying the plate B and anti-friction element C loose from the retainer. The end walls 21—21 are similar in formation except for their opposite disposition and each end wall is centrally offset outwardly to provide oppositely disposed horizontally extending spring pockets 26—26, each of said pockets being of such diameter as to accommodate a spring of considerable size, the pockets opening inwardly toward the center of the bearing and terminating at the inner face of each end wall.

The adjustable bearing plate arrangement B comprises a flat plate 27 and adjusting shims 28. The bearing plate 27 is centrally disposed and rests upon the shims 28 which are disposed between the end walls 21—21 below the spring pockets, the shims 28 being removable from beneath the plate 27 and shims added, removed, or substituted therefor, when it is desired to adjust the vertical height of said plate as hereinafter more fully described.

The anti-friction element C, as shown, is in the form of a truly cylindrical roller disposed in the housing or retainer and adapted to roll 90 back and forth upon the bearing plate 27.

The centering means D—D are two in number, one of the same being disposed upon one side of the roller, and the other upon the opposite side of the roller. The centering means D at one side of the anti-friction element comprise a transmitting member 29 which extends transversely across the housing and is adapted to have its opposite ends abut against the abutments 24—24 on the side walls 20—20 of the housing, to limit its movement toward the element C. The inner face of each transmitting member 29 is curved upon a radius slightly greater than that of the anti-friction element C, as indicated at 30, and the curved face is adapted to bear against said anti-friction element C. The greater radius of curvature of the bearing face 30 of each transmitting member is for the purpose of permitting adjustment 100 105 110

of the vertical height of the anti-friction element C without interfering with the operation of the centering means, as will be understood. Each transmitting member 29 on its rear face is provided with a socket 31 for the reception of one end of a coiled spring 32, said coiled spring fitting into the socket 31 and extending into the pocket 26, whereby the opposite end thereof is in abutment with the end wall 33 of said pocket, the spring operating to press the transmitting member 29 toward the roller, and by reason of the fact that the spring is confined to longitudinal movement in the pocket 26, and engages in the socket 31 of the transmitting member, each centering means D is permitted yieldable movement only in a path substantially parallel to the path of travel of the anti-friction element, while being restrained against movement at an angle to the path of travel of the anti-friction element, or in a vertical direction. The centering means D, at the opposite side of the roller C are identically similar to that just described except for its opposite disposition, and the same reference characters will be utilized for designating like parts of both.

In operation, assuming that the anti-friction element C is moving under load in a right hand direction, as viewed in Fig. 1, the right hand transmitting element 29 is carried therewith compressing the right hand spring 32, while the left hand transmitting member is held relatively stationary by reason of its engagement with the abutments 24-24 at the left hand end of the housing. When the anti-friction element C is freed from load, the energy stored in the spring 32 presses the transmitting member 29 inwardly, which bearing upon the anti-friction element C returns the same toward central position. The operation of the centering means, upon movement of the anti-friction element to the left, as viewed in Fig. 1, is the reverse of that just described. When it is desired to adjust the vertical height of the anti-friction element C, when the truck is removed from the car, a bar may be inserted into the housing through the openings 25 and the anti-friction element C pried out of the housing, the transmitting members 29-29 of course yielding during this operation. One or both of the transmitting members 29-29 are then removed by compressing the springs 32-32, after which the springs 32-32 may be removed so as to render the adjustable bearing plate 27 accessible, and one or more of the shims 28 may be inserted or removed, or other shims substituted therefor, as desired, to adjust the vertical height of the bearing plate. The centering means then may be replaced in position, and the roller pressed into the housing between the transmitting members 29, by allowing the weight of the car to rest

thereon when the truck is replaced in operative position, after which the bearing is again ready for operation.

Referring now to Fig. 4, a slightly different embodiment of the invention is contemplated, and although only one-half of the bearing is disclosed in Fig. 4, it will be understood that the end not shown is identically similar to the portion shown. In this construction a housing A' is provided which includes opposite side walls, one of which is indicated at 50, each of said side walls being vertically arranged and having smooth inner surfaces. The housing is also provided with end walls as indicated at 51, each end wall having a pocket 52 formed therein by offsetting the said end wall 51 outwardly, the end wall 51 and pocket 52 being cut out as indicated at 53 for a purpose hereinafter referred to.

Mounted upon the bottom of the housing is an adjustable bearing plate arrangement B' comprising a bearing plate proper as indicated at 54 and a plurality of shims 55 disposed beneath said bearing plate, the bearing plate 54 and shims 55 being held against longitudinal movement or displacement with reference to the housing A' by central abutments 56 formed at the opposite sides of the housing. The anti-friction element C' is in the form of a truly cylindrical roller and is identically similar to the anti-friction element C heretofore referred to.

Centering means are arranged at opposite sides of the roller in a manner similar to that disclosed in connection with Fig. 1. The centering means at one side of the roller only are shown in Fig. 4, but it will be understood that the centering means not shown are similar to those which are illustrated in Fig. 4. The centering means D', as shown, comprise a transmitting element 57 and a coiled spring 58. The transmitting member 57 has an engaging face 59 adapted to bear against the anti-friction element C', said member 57 being curved as indicated at 60 so as to engage the anti-friction element C above the central axis thereof. The rear face of the transmitting member 57 is provided with a cylindrical extension 61 which telescopically fits into the pocket 52. The transmitting member 57 is also provided with an extension 62 adapted to abut against the end of the bearing plate 54 so as to limit the inward movement of the transmitting member 57, the cut out portion 53 of the end wall 51 and pocket 52 serving to permit movement of the extension 62 with reference to the housing. The spring 58 projects into the cylindrical extension 61 upon the transmitting member 57, and bears upon the rear wall of the transmitting member 57 and upon the end wall of the pocket 52.

In operation, assuming the anti-friction element C' to be moving under the load toward the right as viewed in Fig. 4, the trans-

mitting element 57 will be carried therewith, compressing the spring 58, which operates to urge the anti-friction element C toward central position when load is removed therefrom, 5 the inward movement of the transmitting member 57 being arrested by abutment of the extension 62 with the end of the bearing plate 54. When it is desired to remove the anti-friction element C' the same is forced upwardly, the transmitting members on each side thereof yielding to permit this movement, after which the bearing plate is removed, releasing the transmitting members and springs, which are also removed. The 10 adjusting shims are then changed, after which the springs and transmitting members are reinserted in position, and the bearing plate replaced. The anti-friction element is then pressed into the retainer between the 15 transmitting members.

In the above described arrangements it will be appreciated that the transmitting members and the springs 32—32, have the function of centering the anti-friction element as well as 20 operating to hold each other in assembled relation, while engagement of the centering means with the anti-friction element above the central axis thereof, maintains the same in assembled relation with reference to the 25 retainer; the centering means and anti-friction element being capable of removal when desired by compressing the springs, to release the parts, thereby making the bearing plate arrangement accessible for adjustment.

30 While I have herein shown and described what I now consider the preferred manner of carrying out the invention, the same is merely 35 illustrative, and I contemplate all changes and modifications that come within the scope 40 of the claims appended hereto.

I claim:

1. In an anti-friction bearing of the character described, the combination with a housing having side and end walls, said side walls being provided with inwardly extending means providing abutments, and said end walls having horizontally extending pockets open at their inner ends; an adjustable bearing plate comprising adjusting shims and a bearing plate proper resting upon said shims; an anti-friction roller adapted to move back and forth on said bearing plate; transmitting members having curved faces engaging said anti-friction element and adapted to 55 contact the abutments on the side walls of the said retainer to limit inward movement thereof, each of said transmitting members being provided with a socket upon its rear face; and a coiled spring disposed in each of 60 said pockets bearing upon the related transmitting member and fitting into the socket of the same.

2. In an anti-friction bearing, the combination with an anti-friction element having

a curved bearing surface; of a housing for 65 said anti-friction element having an opening through which said element may be inserted and removed; a bearing plate disposed in said housing and co-operating with the curved bearing surface of said anti-friction element; 70 means for adjusting the vertical height of said bearing plate, said means being accessible through said opening when the anti-friction element is removed; centering mechanism interengaged with said housing, 75 and including follower members arranged at opposite sides of said anti-friction element and adapted to engage the curved bearing surface of the same above the central axis 80 thereof to maintain said element in assembled relation with respect to the housing; and resilient means opposing movement of each follower, and said follower members being adapted to be forced apart against the tension of the resilient means thereby freeing 85 the anti-friction means to permit the same to be removed through said opening, removal of said anti-friction element also freeing said followers for removal through said 90 opening.

3. In an anti-friction bearing, the combination with a housing adapted to be secured to a bolster, and provided with an opening; of an anti-friction roller element within the housing adapted to move back and forth and project through said opening into engagement with an opposed bolster, said anti-friction element being insertable and removable through said opening when said housing is 95 in position on said bolster; of centering 100 means for said anti-friction element including centrally arranged follower members having curved bearing surfaces engaging said element, one of said members being disposed at each side of said anti-friction element and in the path of the bearing surface thereof; means on said housing providing centrally disposed pockets telescopically receiving said members; means yieldingly opposing movement of each member independently, said members being adapted to be forced apart against said yielding means to effect removal of the roller through said 110 opening.

4. In an anti-friction bearing, the combination with a housing provided with a bearing surface; of an anti-friction roller element adapted to move back and forth upon said bearing surface, said housing having an opening through which the roller element projects, said roller element being insertable and removable through said opening; and centering mechanism interengaged with said housing, and including a follower disposed 115 at each side of the roller element and in the path of the bearing surface and in line with said opening thereof, each of said followers having a curved bearing surface engaging 120 125

the periphery of the roller, said curved surfaces extending above the center of the roller to maintain the same assembled with the housing; and resilient means adapted to urge said followers toward the roller element, said followers being adapted to be forced apart to permit removal of the roller through said

opening, thereby freeing said followers for vertical removal through said opening of the housing.

In witness that I claim the foregoing I have hereunto subscribed my name this 28th day of January 1926.

JOHN F. O'CONNOR.
